UNITED STATES PATENT OFFICE.

WALTER M. AUSTIN, OF SWISSVALE, AND ROBERT FRANKLIN RINGLE, OF ZELIENOPLE, PENNSYLVANIA, ASSIGNORS TO HERMAN PNEUMATIC MACHINE COMPANY, OF ZELIENOPLE, PENNSYLVANIA.

TURNOVER AND PATTERN-DRAWING DEVICE.

1,243,030.

Specification of Letters Patent.

Patented Oct. 16, 1917.

Application filed March 1, 1913. Serial No. 751,425.

To all whom it may concern:

Be it known that we, WALTER M. AUSTIN, a citizen of the United States, and resident of Swissvale, in the county of Allegheny, and ROBERT FRANKLIN RINGLE, a citizen of the United States, and resident of Zelienople, in the county of Butler, both in the State of Pennsylvania, have invented a new and useful Improvement in Turnover and Pattern-Drawing Devices; and we do hereby declare the following to be a full, clear, and exact description thereof.

Our invention relates to turnover and pattern drawing devices and has special reference to such devices for use with sand molding machines, known as the jarring type, wherein the pattern is placed in a casing or flask and sand placed around the same and this is then jarred by pneumatic means until the sand has attained the required degree of solidity.

The object of our invention is to provide a cheap, simple and efficient form of turnover and pattern drawing device for use in connection with sand molding machines whereby the pattern and the sand filled flask around the same may be turned over and the pattern removed from the same without disturbing the molded sand around such pattern and without any handling except by mechanical means.

Our invention consists, generally stated, in the novel arrangement, construction and combination of parts as hereinafter more specifically set forth and described and particularly pointed out in the claims.

To enable others skilled in the art to which our invention appertains to construct and use our improved turnover and pattern drawing device we will describe the same more fully, referring to the accompanying drawings, in which—

Figure 1 is a side elevation of the improved turnover and pattern drawing device together with a jarring machine, such device being shown in its position during the jarring operation.

Fig. 2 is a top plan view of the same.

Fig. 3 is a side elevation of the turnover and pattern drawing device after the pattern and flask have been turned over.

Fig. 4 is a side elevation of the turnover and pattern drawing device showing the flask in a position ready to be withdrawn from around the pattern. 55

Fig. 5 is a side elevation of the turnover and pattern drawing device showing the pattern withdrawn from the flask.

Fig. 6 is a cross-sectional view of the device on the line 6—6 of Fig. 2. 60

Fig. 7 is a cross-sectional view of the device on the line 7—7 of Fig. 2.

Fig. 8 is a top plan view of the equalizing table used in withdrawing the pattern from the mold. 65

Fig. 9 is an end view of the same.

Fig. 10 is a side view of one of the turnover arms.

Fig. 11 is a sectional view of the leveling and shock absorbing device. 70

Fig. 12 is an end view of the turnover plate.

Fig. 13 is an inner end view of the crank case cover.

Fig. 14 is a side view of the main shaft. 75

Fig. 15 is a longitudinal sectional view of the vibrator employed.

Figs. 16 and 16^a are side and front views of the trunnion plate employed.

Fig. 17 is a perspective view of the upright extension used on the end of the turnover plate. 80

Fig. 18 is a side view of the locking device.

Fig. 19 is a cross sectional view of the same in the line α α Fig. 1. 85

Fig. 20 is a partial view looking in direction of arrow Fig. 1.

As illustrated in the drawings our improved turnover and pattern drawing device A is 90 used in connection with sand molding machines of the jarring type B, such as shown in Fig. 1, wherein the machine is provided with a table 1, which has a plunger 2 below the same and connected therewith and such plunger operates in the cylinder 3. Around the jarring machine B and in close proximity to the edges or flanges 4 of the table 1 is a casing 5 and such casing is provided at suitable points, such as the corners of the same, with projections 6, which have recesses 7 within the same. The recesses 7 in 95 100

the projections 6 provide for the reception of a resilient block 8 in each of the same and such resilient blocks have a metal block 9 above the same which extends slightly above the upper edge of said projections. Extending downwardly from the under face of the table 1 is a series of posts 10 and such posts are distributed one directly above each of the projections 6, and adapted to rest on the upper face of the metal blocks 9. At the lower end of the cylinder 3 is a port 11, which has a valve mechanism 12 connecting therewith so that the plunger 2 may be raised automatically by means of operating fluid such as compressed air entering from the pipe 13 into the valve mechanism 12 and the port 11 under said plunger in order to raise the same within said cylinder. The valve mechanism is operated in such a manner that when the plunger 2 in the cylinder 3 has reached the desired height the operating fluid below the same is exhausted therefrom and the plunger allowed to drop within said cylinder. The posts 10 extending downward from the bottom of the table 1, where the pattern *b* rests, will thus strike on the tops of the metal blocks 9 and the sand within the flask *a* will be jarred, whereas, the plunger 2 will be raised immediately in the cylinder 3 so that the jarring operation is repeated eighty to one hundred times a minute.

The turnover and pattern drawing device B has a frame or outer casing 14, in which is located a cylinder 15, and such cylinder extends entirely through the said frame in a horizontal direction and has a curved crank case cover at the inner end thereof, which is for the purpose hereinafter described. The frame 14 is also provided with a main shaft 17 which is provided at suitable points throughout the length of the same with square portions 18, while the remainder of the shaft is round for the purpose of operating in suitable bearings.

Within the cylinder 15 is a piston 19, which is adapted to move in a direction shown by the arrow when the pattern is being turned over by means of operating fluid such as compressed air entering through the pipe 15^a, and such piston is provided with a connecting rod 20, which is pivotally connected to said piston, as later described. The front end of the connecting rod 20 is connected to a crank 21 by a pivotal connection 22 at one end of the same, and such crank is connected at its other end to one of the square portions 18 on the shaft 17.

The crank case cover 16 is provided with a flange 23 which has a series of holes 24 which are adapted to receive rods 25 and such rods extend inwardly in order to provide suitable guides for spiral springs 25^a which are for the purpose hereinafter described.

The turnover plate 26 is adapted to rest upon the table 1 while the jarring operation is being carried on in the jarring machine and said turnover plate is provided with lugs 27 which have under cut grooves 28 for receiving the heads of the tightening bolts of flask clamps 29 as later described. The turnover plate 26 is further provided with offset portions 30 which have an upright extension 31 fastened thereto by means of a flange 32 while said upright extension is provided with a tapered trunnion 33 as later described.

At each end of the main shaft 17 and firmly secured to the square portions 18 thereon is a turnover arm 34 which has a downwardly curved inner end 34' and an upwardly curved outer end 34'', said outer end being provided with a round hole 35 for receiving a pin 36 which also enters the round hole 37 of the trunnion plate 38. This trunnion plate 38 is adapted to stand in a vertical position when the turnover arms 34 are in a lowered position as shown in Fig. 1 and is provided with a tapered groove 39 in the inner face of the same for receiving the trunnion 33 on the upright extension 31 carried by the turnover plate 26 at suitable times. The trunnion plate 38 is further provided with a lug 40 which extends outwardly from the outer face of the same while at the upper end of said plate is a hole 41 as later described.

The turnover arm 34 is provided at a point near the outer end of the same with an enlarged portion 42 which has a chamber 42' in the same and a hole 42^a extending into said chamber from the upper side of said portion while the lower end of the chamber is closed by a suitable cover 43. The chamber 42' is provided with a spiral spring 44 while a pin 45 extends through the hole 42^a and into the chamber 42' where it is provided with a plate 46 for compressing the said spring from above. The bottom of the chamber 42' is also provided with a plate 46' which is adjusted to position by means of a screw 47 in order to provide the proper amount of tension on the spiral spring 44.

At one side of the turnover plate 26 a vibrator 48 is connected and such vibrator consists of a body 49 and end caps 50 while a plunger or hammer 51 is adapted to be pushed back and forth therein by means of operating fluid admitted to the port 52 and alternately admitted from such port to the passageways 53 and 54 whence it passes to the opposite ends of said plunger. This vibrator 48 is for the purpose of gently vibrating the turnover plate 26 so that the pattern *b* in the flask *a* can be readily withdrawn from the sand and the molded sand in said flask maintained in position while the spring 55 in said vibrator is to prevent the plunger 51 from stopping on a dead-center.

and thus shutting off the supply of operating fluid from the passageways 53 and 54.

At each extreme side of the frame 14 and fitting over the main shaft 17 is a bearing cap 56 which is provided with an extension 57, said extension having a slot 58 therein and a hole 59 entirely through the same for the purpose of receiving a pin 60 which pin extends through said slot and through 10 the swivel end 61 of the rod 62 when the same is in position so as to allow the said rod to be revolved on said pin as later described. The rod 62 is provided with a left handed threaded portion 63 at its other end 15 so as to provide for a turnbuckle 64 which engages with said thread and with a similar right handed thread on the end of a rod 65 in order to provide for the adjustment of the distance between the ends of the respective rods. At the outer end of the rod 65 is a locking piece 66 which has a curved groove 67 in the offset portion 68 while the outer side of the same is provided with a hole 69 for receiving a pin 70 which pin is 20 adapted to pass through the said hole and the hole 41 in the upper end of the trunnion plate 38 in order to fasten the same together and provide for the rotation of said parts.

30 At one side of the cylinder 15 is another vertical cylinder 71 which has a plunger 72 within the same and an operating fluid admission port 73 for admitting operating fluid to raise said plunger in said cylinder 35 while the top of said plunger is provided with a plate 74 which rises therewith and carries the equalizing table 74^a. This plate 74 has a friction pad 75 on each corner of the same and the center of said plate is provided with a pair of lugs 76 which are adapted to receive a fulcrum lever 77 between the same while a fulcrum pin 78 extends through said lever and lugs in order to form a pivotal connection therewith. A 40 spring rod 79 extends out over the sides of the plate 74 and passes through a side beam 80 on each side of said table and has a friction spring 81 on each end thereof while a nut 82 holds said spring in place and provides for the tension of said bars against the friction pads 75 on the corners of the plate 74. The fulcrum lever 77 has an end lever 83 at each end of the same and pivotally connected therewith at its center and 45 such end lever is adapted to be pivotally connected at each end of the same to one of the side beams 80 by means of pivotal bearing pads 84.

On each side of the cylinder 71 is an extension 85 through which a rod 86 passes and each rod is fastened to the under side of the plate 74 by its upper end and a spiral spring 87 is located loosely on said rod and rests on the top of said extension. The 60 lower end of each rod 86 is also provided

with a spiral spring 88 which works loosely thereon and rests upon a washer 89 which is supported by a nut 90.

The use and operation of our improved turnover and pattern drawing device is as 70 follows:

The turnover plate 26 is placed on the table 1 as shown in Fig. 1 and the pattern b is secured thereto such as by wood screws whereupon the flask a is placed around said 75 pattern and molding sand is heaped into said flask. The jarring machine B is then set in motion by means of the operating fluid entering the valve mechanism 12 from the pipe 13 and passing under the plunger 2 through the port 11 so that the said plunger is thus raised in the cylinder 3 until the desired height is attained at which time the operating fluid is exhausted from the same and the plunger drops in said 80 cylinder so that the posts 10 will strike upon the metal blocks 9 in the projections 6 and thus jar the sand in the flask a. As soon as the table 1 and plunger 2 are thus dropped and the sand has been jarred in 85 said flask a the operating fluid will again be admitted to the valve mechanism 12 and the operation repeated until the sand in said flask has been jarred to the required degree 90 of solidity. During this operation the 95 trunnions 33 on the upright extensions 31 have been entering and leaving the tapered groove 39 in the inner face of the trunnion plate 38 but the bottoms of said trunnions have not struck the bottoms of said grooves 100 as sufficient clearance is left to prevent the same from striking. During this operation the turnover arms 34 have remained perfectly stationary and the device is not used until after the molding sand in the flask 105 a has been jarred to the required degree of 105 solidity.

After the jarring operation is completed the flask a will be covered by a bottom board 91 and the flask and board then fastened 110 to the turnover plate 26 by means of the clamps 29 which engage with the tongue grooves 28 in said plate and over the top of said board.

At this stage operating fluid is admitted 115 to the rear of the piston 19 in the cylinder 15 by means of the pipe 15^a connecting therewith so that the said piston will move forward in said cylinder which operation will push the connecting rod 20 forward and 120 thus rotate the crank 21 which is securely fastened to one of the square portions 18 of the shaft 17 so that the said shaft will thus be also rotated by such operation. Since the turnover arms 34 are each connected to a square portion of the shaft 17 125 this movement will raise the same with the center of said shaft as the axis of rotation. The trunnions 33 will engage with the tapered grooves 39 in the inner face of the 130

trunnion plate 38 and as the turnover arms 34 are raised the turnover plate 26 will be lifted carrying with it the pattern *b* and the sand filled flask *a*.

- 5 It will be noticed that the distance between the centers of the main shaft 17 and the pin 36 in the hole 35 on the end of the turnover arm 34 is considerably greater than the distance between the centers of the pin 10 in the hole 59 on the extension 57 and the pin 70 in the hole 69 on the locking piece 66 so that as the arms 34 are raised the rod 65 will tend to pull the trunnion plate 38 downward which will turn the turnover plate 26 15 over and this difference between centers is just sufficient to rotate the said turnover plate one half revolution by the time the arms 34 have reached a vertical position. As the turnover plate 26 is thus rotated and 20 the trunnion plate 38 is pulled over by the rod 65 the curved groove 67 in the locking piece 66 will extend over the top of the trunnion 38 and tapered groove 39 so as to prevent said trunnion from leaving said tapered groove and when the arms 34 have gone a short distance the turnover plate 26 and flask *a* thereon will be supported by said trunnion resting in said curved groove. When such arms have reached a vertical position 25 the lug 40 on the trunnion plate 38 will strike against the pin 45 in the enlarged portion 42 so that the spiral spring 44 in the chamber 42' will be compressed by the plate 46 and the jarring taken from the mold and arms 34 so that said arms can come to rest without any shock.
- The spiral spring 44 in the chamber 42' will also serve as a leveling device for the turnover plate as the tension thereon can be 40 regulated by means of adjusting the plate 46' which is governed by the screw 47.
- During this operation the connecting rod 20 will have advanced so that the outer end of the same connecting to the crank 21 will 45 extend into the interior of the crank case cover 16 and the spiral springs 25^a will be compressed by the piston 19 which also aids in preventing shocks to the working parts and the mold.
- 50 The flask and turnover plate have now been revolved one half revolution so that the flask is underneath and directly above the equalizing table 74^a carried by the plate 74 on the plunger 72. The plunger 72 is 55 now raised in the cylinder 71 by means of operating fluid which is admitted to said cylinder from the port 73 and the equalizing table 74^a is pressed against the bottom board 91 with sufficient force to overcome the pressure of the side beams 80 against the friction pads 75 which is operated by the friction springs 81 so that said side beams will engage firmly with the bottom of said board on account of said table being adapted to 60 assume any required position to provide for

irregularities in such surface. At the same time the spiral springs 88 which operate loosely on the rods 86 will prevent the plunger 72 and table 74^a from shocks by their bearing against the lower end of the extensions 85 and being compressed by the washers 89 on the ends of such rods.

The clamps 29 are now removed from the flask *a* and turnover plate 26 and the compressed air is admitted to the vibrator 48 so 75 that the pattern is gently vibrated in order to loosen the same from the molded sand which is necessary in order to enable the same to be withdrawn without injury to the mold. The operating fluid is now slowly exhausted from the cylinder 71 and the plunger 72 will thus be lowered therein so that the flask *a* containing the molded sand will be lowered on the equalizing table 74^a and the pattern *b* remain suspended from 80 the turnover plate 26. As the plunger 72 nears the bottom of the cylinder 71 the spiral springs 87 which rest on the top of the extensions 85 will be engaged by the bottom of the plate 74 and compressed so that said 85 plunger will be stopped gently without any jar or vibration on the molded sand in the flask *a* resting on the equalizing table 74^a.

The turnover plate 26 is now ready to be returned to its original position on the table 95 1 of the jarring machine B and this is accomplished by means of exhausting the operating fluid from the cylinder 15. The turnover arms 34 are when in their vertical position supported by the main shaft 17 100 and will not fall of their own weight until pushed over from such vertical position so that the angle between such position and the original position is less than 90 degrees, so to accomplish this purpose the spiral springs 105 25^a which are under compression when the arms 34 are in a vertical position will when the operating fluid is exhausted press the piston 19 outward and thus draw the connecting rod with the same which will rotate 110 the shaft 17 through the medium of the crank 21 and thus throw the said arms backward after which the weight of the same and the turnover plate 26 will be sufficient to 115 exhaust the operating fluid from the cylinder 15 and thus allow the said plate and turnover arms to assume their original position.

It will thus be seen that after the sand in the flask has been completely jarred to the 120 required degree of solidity the same will be mechanically turned over and the pattern drawn from the same so that the mold can be taken away and the liquid metal poured into the same which will be of great advantage where the castings are of large size and hard to handle.

The equalizing table 74^a is so constructed that it can assume any plane desired under the flask so as to allow for the irregularities 125 130

of the bottom boards and to provide a steady surface for supporting the flask containing the molded sand as the pattern is being withdrawn from the same. On account of its peculiar construction it can be pressed against the flask or bottom board and made to assume any reasonable plane necessary while the tension of the friction springs will be great enough to prevent the weight 10 of the flask and molded sand from changing the plane produced by the surface of the bottom of the flask and bottom board when the operating fluid acted upon the plunger carrying the same.

15 It will further be noticed that the device will not require any great amount of space for installation as practically all of the same with the exception of the turnover arms and equalizing table can be placed below the floor line which has been done where such machines have been installed.

20 Various modifications and changes in the design, construction and application of our improved turnover and pattern drawing device may be resorted to without departing from the spirit of the invention or sacrificing any of its advantages.

25 What we claim as our invention and desire to secure by Letters Patent is:—

30 1. A turnover and pattern drawing device for sand molding machines comprising a plate for carrying a pattern and a flask, said plate being adapted to rest on the table of said molding machine during the jarring 35 operation, means for engaging with said plate to raise the same so as to suspend said pattern and flask, means for turning said plate relatively to said raising means during the raising operation, means for operating 40 said first named means, and means for lowering said flask from around said pattern.

45 2. A turnover and pattern drawing device for sand molding machines comprising a plate for carrying a pattern and a flask, said plate being adapted to rest on the table of said molding machine during the jarring operation, turnover arms for engaging with said plate to raise the same so as to suspend said pattern and flask, means for turning 50 said plate relatively to said raising means during the raising operation, means for operating said turnover arms, and means for lowering said flask from around said pattern.

55 3. A turnover and pattern drawing device for sand molding machines comprising a plate for carrying a pattern and a flask, said plate being adapted to rest on the table of said molding machine during the jarring 60 operation, means for engaging with said plate to raise the same so as to suspend said pattern and flask, means for turning said plate relatively to said raising means during the raising operation, a cylinder containing a piston for operating said first-

named means, and means for lowering said flask from around said pattern.

4. A turnover and pattern drawing device for sand molding machines comprising a plate for carrying a pattern and a flask, said plate being adapted to rest on the table of said molding machine during the jarring operation, turnover arms for engaging with said plate to raise the same so as to suspend 70 said pattern and flask, means for turning said plate relatively to said raising means during the raising operation, a cylinder containing a piston for operating said turnover arms, and means for lowering said flask from around said pattern.

5. A turnover and pattern drawing device for sand molding machines comprising a plate for carrying a pattern and a flask, said plate being adapted to rest on the table of said molding machine during the jarring 80 operation, means for engaging with said plate to raise the same so as to suspend said pattern and flask, means for turning said plate relatively to said raising means during the raising operation, means for operating 85 said first named means, and a cylinder containing a plunger for lowering said flask from around said pattern.

6. A turnover and pattern drawing device for sand molding machines comprising a plate for carrying a pattern and a flask, said plate being adapted to rest on the table of said molding machine during the jarring 90 operation, turnover arms for engaging with said plate to raise the same so as to suspend said pattern and flask, means for turning said plate relatively to said raising means during the raising operation, means for operating 95 said turnover arms, and a cylinder containing a plunger for lowering said flask from around said pattern.

7. A turnover and pattern drawing device for sand molding machines comprising a plate for carrying a pattern and a flask, said plate being adapted to rest on the table 100 of said molding machine during the jarring operation, means for engaging with said plate to raise the same so as to suspend said pattern and flask, means for turning said plate relatively to said raising means during 105 the raising operation, a cylinder containing a piston for operating said first-named means, and a cylinder containing a plunger for lowering said flask from around said pattern.

8. A turnover and pattern drawing device for sand molding machines comprising a plate for carrying a pattern and a flask, said plate being adapted to rest on the table of said molding machine during the jarring 110 operation, turnover arms for engaging with said plate to raise the same so as to suspend said pattern and flask, means for turning said plate relatively to said raising means during 115 the raising operation, a cylinder containing a piston for operating said first-named means, and a cylinder containing a plunger for lowering said flask from around said pattern.

120

- containing a piston for operating said turnover arms, and a cylinder containing a plunger for lowering said flask from around said pattern.

5 9. A turnover and pattern drawing device for sand molding machines comprising a plate for carrying a pattern and a flask, turnover arms for engaging with said plate to raise the same, means for turning said plate relatively to said raising means during the raising operation, a cylinder containing a piston for operating said turnover arms, a cylinder containing a plunger for lowering said flask from around said pattern, and springs in said first named cylinder for returning said turnover arms to their initial position.

10 10. A turnover and pattern drawing device for sand molding machines, comprising a plate for carrying a pattern and a flask, means for engaging with said plate to raise the same, means for turning said plate relatively to said raising means during the raising operation, means for regulating the stroke of said first named means and absorbing shocks, and means for lowering said flask from around said pattern.

15 11. A turnover and pattern drawing device for sand molding machines, comprising a plate for carrying a pattern and a flask, means for engaging with said plate to raise the same, means for turning said plate relatively to said raising means during the raising operation, means for regulating the stroke of said first named means and absorbing shocks, and a cylinder containing a plunger for lowering said flask from around said pattern.

20 12. A turnover and pattern drawing device for sand molding machines comprising a plate for carrying a pattern and a flask, means for engaging with said plate to raise the same, means for turning said plate relatively to said raising means during the raising operation, a shock absorber for regulating the stroke of said first-named means and absorbing shocks, and means for lowering said flask from around said pattern.

25 13. A turnover and pattern drawing device for sand molding machines comprising a plate for carrying a pattern and a flask, means for engaging with said plate to raise the same, means for turning said plate relatively to said raising means during the raising operation, a shock absorber for regulating the stroke of said first-named means and absorbing shocks, and a cylinder containing a plunger for lowering said flask from around said pattern.

30 14. A turnover and pattern drawing device for sand molding machines comprising a plate for carrying a pattern and a flask, means for engaging with said plate to raise the same, means for turning said plate relatively to said raising means during the raising operation, means for operating said turnover arms, and means for lowering said flask from around said pattern.

35 15. A turnover and pattern drawing device for sand molding machines comprising a plate for carrying a pattern and a flask, turnover arms for engaging with said plate to raise the same, means for turning said plate relatively to said raising means during the raising operation, a cylinder containing a piston for operating said turnover arms, and means for lowering said flask from around said pattern.

40 16. A turnover and pattern drawing device for sand molding machines comprising a plate for carrying a pattern and a flask, said plate being adapted to rest on the table of said molding machine during the jarring operation, turnover arms having rods so positioned as to turn said plate while the same is being raised, so as to suspend said pattern and flask, means for operating said turnover arms, and means for lowering said flask from around said pattern.

45 17. A turnover and pattern drawing device for sand molding machines comprising a plate for carrying a pattern and a flask, said plate being adapted to rest on the table of said molding machine during the jarring operation, turnover arms having rods so positioned as to turn said plate while the same is being raised, so as to suspend said pattern and flask, a cylinder having a piston for operating said turnover arms, and means for lowering said flask from around said pattern.

50 18. A turnover and pattern drawing device for sand molding machines comprising a plate for carrying a pattern and a flask, said plate being adapted to rest on the table of said molding machine during the jarring operation, turnover arms having rods so positioned as to turn said plate while the same is being raised, so as to suspend said pattern and flask, a cylinder having a piston for operating said turnover arms, and a cylinder containing a plunger coöperating with said flask to lower the same from around said pattern.

55 19. A turnover and pattern drawing device for sand molding machines comprising a plate for carrying a pattern and a flask, said plate being adapted to rest on the table of said molding machine during the jarring operation, means for engaging with said plate to raise the same so as to suspend said pattern and flask, means for turning said plate relatively to said raising means during the raising operation, means for operating said first named means, and means carrying an equalizing table for assuming the lower level of said flask to lower the same from around said pattern.

60 20. A turnover and pattern drawing de-

- vice for sand molding machines comprising a plate for carrying a pattern and a flask, said plate being adapted to rest on the table of said molding machine during the jarring operation, turnover arms for engaging with said plate to raise the same so as to suspend said pattern and flask, means for turning said plate relatively to said raising means during the raising operation, means for operating said turnover arms, and means carrying an equalizing table for assuming the lower level of said flask to lower the same from around said pattern.
21. A turnover and pattern drawing device for sand molding machines comprising a plate for carrying a pattern and a flask, said plate being adapted to rest on the table of said molding machine during the jarring operation, means for engaging with said plate to raise the same so as to suspend said pattern and flask, means for turning said plate relatively to said raising means during the raising operation, a cylinder containing a piston for operating said first-named means, and means carrying an equalizing table for assuming the lower level of said flask to lower the same from around said pattern.
22. A turnover and pattern drawing device for sand molding machines comprising a plate for carrying a pattern and a flask, said plate being adapted to rest on the table of said molding machine during the jarring operation, turnover arms for engaging with said plate to raise the same so as to suspend said pattern and flask, means for turning said plate relatively to said raising means during the raising operation, a cylinder containing a piston for operating said turnover arms, and means carrying an equalizing table for assuming the lower level of said flask to lower the same from around said pattern.
23. A turnover and pattern drawing device for sand molding machines comprising a plate for carrying a pattern and a flask, said plate being adapted to rest on the table of said molding machine during the jarring operation, means for engaging with said plate to raise the same so as to suspend said pattern and flask, means for turning said plate relatively to said raising means during the raising operation, means for operating said first named means, and a cylinder containing a plunger carrying an equalizing table for assuming the lower level of said flask to lower the same from around said pattern.
24. A turnover and pattern drawing device for sand molding machines comprising a plate for carrying a pattern and a flask, said plate being adapted to rest on the table of said molding machine during the jarring operation, turnover arms for engaging with said plate to raise the same so as to suspend
- said pattern and flask, means for turning said plate relatively to said raising means during the raising operation, means for operating said turnover arms, and a cylinder containing a plunger carrying an equalizing table for assuming the lower level of said flask to lower the same from around said pattern.
25. A turnover and pattern drawing device for sand molding machines comprising a plate for carrying a pattern and a flask, said plate being adapted to rest on the table of said molding machine during the jarring operation, means for engaging with said plate to raise the same so as to suspend said pattern and flask, means for turning said plate relatively to said raising means during the raising operation, a cylinder containing a piston for operating said first-named means, and a cylinder containing a plunger carrying an equalizing table for assuming the lower level of said flask to lower the same from around said pattern.
26. A turnover and pattern drawing device for sand molding machines comprising a plate for carrying a pattern and a flask, said plate being adapted to rest on the table of said molding machine during the jarring operation, turnover arms for engaging with said plate to raise the same so as to suspend said pattern and flask, means for turning said plate relatively to said raising means during the raising operation, a cylinder containing a piston for operating said turnover arms, and a cylinder containing a plunger carrying an equalizing table for assuming the lower level of said flask to lower the same from around said pattern.
27. A turnover and pattern drawing device for sand molding machines comprising a plate for carrying a pattern and a flask, said plate being adapted to rest on the table of said molding machine during the jarring operation, means for engaging with said plate to raise the same so as to suspend said pattern and flask, means for turning said plate relatively to said raising means during the raising operation, means for operating said first named means, and means carrying an equalizing table adapted to be pressed against said flask to assume the lower level of the same and for maintaining said level while said flask is being withdrawn from around said pattern.
28. A turnover and pattern drawing device for sand molding machines comprising a plate for carrying a pattern and a flask, said plate being adapted to rest on the table of said molding machine during the jarring operation, turnover arms for engaging with said plate to raise the same so as to suspend said pattern and flask, means for turning said plate relatively to said raising means during the raising operation, means for operating said turnover arms,

- and means carrying an equalizing table adapted to be pressed against said flask to assume the lower level of the same and for maintaining said level while said flask is being withdrawn from around said pattern.
29. A turnover and pattern drawing device for sand molding machines comprising a plate for carrying a pattern and a flask, said plate being adapted to rest on the table of said molding machine during the jarring operation, means for engaging with said plate to raise the same so as to suspend said pattern and flask, means for turning said plate relatively to said raising means during the raising operation, a cylinder containing a piston for operating said first-named means, and means carrying an equalizing table adapted to be pressed against said flask to assume the lower level of the same and for maintaining said level while said flask is being withdrawn from around said pattern.
30. A turnover and pattern drawing device for sand molding machines comprising a plate for carrying a pattern and a flask, said plate being adapted to rest on the table of said molding machine during the jarring operation, turnover arms for engaging with said plate to raise the same so as to suspend said pattern and flask, means for turning said plate relatively to said raising means during the raising operation, a cylinder containing a piston for operating said turnover arms, and means carrying an equalizing table adapted to be pressed against said flask to assume the lower level of the same and for maintaining said level while said flask is being withdrawn from around said pattern.
31. A turnover and pattern drawing device for sand molding machines comprising a plate for carrying a pattern and a flask, said plate being adapted to rest on the table of said molding machine during the jarring operation, means for engaging with said plate to raise the same so as to suspend said pattern and flask, means for turning said plate relatively to said raising means during the raising operation, means for operating said first-named means, and a cylinder containing a plunger carrying an equalizing table adapted to be pressed against said flask to assume the lower level of the same and for maintaining said level while said flask is being withdrawn from around said pattern.
32. A turnover and pattern drawing device for sand molding machines comprising a plate for carrying a pattern and a flask, said plate being adapted to rest on the table of said molding machine during the jarring operation, turnover arms for engaging with said plate to raise the same so as to suspend said pattern and flask, means for turning said plate relatively to said raising means
- during the raising operation, means for operating said turnover arms, and a cylinder containing a plunger carrying an equalizing table adapted to be pressed against said flask to assume the lower level of the same and for maintaining said level while said flask is being withdrawn from around said pattern.
33. A turnover and pattern drawing device for sand molding machines comprising a plate for carrying a pattern and a flask, said plate being adapted to rest on the table of said molding machine during the jarring operation, means for engaging with said plate to raise the same so as to suspend said pattern and flask, means for turning said plate relatively to said raising means during the raising operation, a cylinder containing a piston for operating said first-named means, and a cylinder containing a plunger carrying an equalizing table adapted to be pressed against said flask to assume the lower level of the same and for maintaining said level while said flask is being withdrawn from around said pattern.
34. A turnover and pattern drawing device for sand molding machines comprising a plate for carrying a pattern and a flask, said plate being adapted to rest on the table of said molding machine during the jarring operation, turnover arms for engaging with said plate to raise the same so as to suspend said pattern and flask, means for turning said plate relatively to said raising means during the raising operation, a cylinder containing a piston for operating said turnover arms, and a cylinder containing a plunger carrying an equalizing table adapted to be pressed against said flask to assume the lower level of the same and for maintaining said level while said flask is being withdrawn from around said pattern.
35. In a flask turnover device, a flask support, means for raising said flask support, and means for turning said flask support relatively to said raising means.
36. In a flask turnover device, a flask support, means for raising said flask support, and means for turning said flask support relatively to said raising means during the operation of the latter.
37. In a flask turnover device, a flask support, means for raising said flask support, means for connecting said flask support with said raising means, so as normally to permit ready movement, means for turning said support relatively to said raising means during the operation of the latter, and means for locking said connection means during the operation of said turning means.
38. In a molding machine, the combination with a roll-over table, of means for raising and lowering said roll-over table, a rotatable member connected with the roll-over table, and a member anchored at its lower

end extending upwardly beside the machine, fastened to and engaging with the aforesaid rotatable member whereby the table is rolled over as it is raised.

- 5 39. In a molding machine, the combination with a jarring table, of a roll over molding table, means for raising and lowering said roll over molding table, and means for causing the roll-over molding table 10 to roll over as it is raised, the last mentioned means including a loose connection which permits the roll over molding table to jar with the jarring table.
40. In a molding machine, the combination 15 with a roll-over table, of means for raising

and lowering said roll-over table, a rotatable member connected with the roll-over table, a member having articulated parts anchored at one end with respect to the roll-over table and at its other end engaging with the 20 rotatable member whereby the table is rolled over as it is raised.

In testimony whereof, we the said **WALTER M. AUSTIN** and **ROBERT FRANKLIN RINGLE**, have hereunto set our hands.

WALTER M. AUSTIN.
ROBERT FRANKLIN RINGLE.
